UNITED STATES PATENT OFFICE.

JAMES H. REED, OF BROOKLYN, NEW YORK.

GRINDING-MACHINE.

SPECIFICATION forming part of Letters Patent No. 291,587, dated January 8, 1884.

Application filed May 10, 1883. (No model.)

To all whom it may concern:

Be it known that I, JAMES H. REED, of the city of Brooklyn, county of Kings, State of New York, have invented certain new and useful Improvements in Machines for Grinding the Edges and Beveled Edges of Plate-Glass or other Materials, of which the following is a specification.

This invention relates to that class of machines called "grinding" machines; and it has for its object improvements in the construction of same, whereby the edges of the material to be ground can be adjusted more readily and with greater precision to the stone or mill than by any other device.

To describe my invention more fully, so that those skilled in the art can understand the same, I will now refer to the accompanying drawings, of which—

Figure 1 is a side elevation of grinding-machine, showing my improvements. Fig. 2 is a plan view of same. Fig. 3 is a sectional view on line $x-x$, showing table in another position.

a represents the horizontal stone or metallic mill, supported in frame a' , driven by pulley a'' , by which the edge or beveled edge of the glass or other material is ground. In the use of the metallic mills sand or other abrading substances are used.

$b b'$ are the rails or ways fastened to the frames $c c' c''$, on which the carriage d , supported by the grooved wheels $d' d'' d''' d''''$, move backward and forward freely the length of the ways $b b'$.

Pivoted to the carriage d by means of the adjustable centers $e e'$ is the table f , controlled and kept in position by the levers $g g'$, fastened to the carriage d at the points $h h'$ and to the under side of the table f by means of the brackets $i i'$. The table f is raised or lowered by means of the curved racks $j j'$, pivoted to the under side of the table f at the points $k k'$, and the pinions $l l'$, fastened to the shaft m , working in the bearings $n n'$ on the carriage d . The racks $j j'$ are held in gear to the pinions $l l'$ by means of guides or braces $o o'$, also fastened to the carriage d .

Upon the shaft m is a hand-wheel, p , for the purpose of working shaft m in direction as may be required when table f is raised or lowered

to the angle desired. The hand-wheel is firmly clamped by means of the clamp q , which is held rigidly to the carriage d by the hand-screw r , by which means the table f is firmly held and easily adjusted at any desired angle. The table f , being pivoted at the adjustable centers $e e'$, is raised or lowered by the eccentrics $s s'$, which work in straps $t t'$, the eccentrics $s s'$ being fastened firmly to shaft u , which works in bearings $v v'$, fastened to the carriage d . The shaft u is worked by means of the hand-wheel w , which is secured to same. When the table f is adjusted to the required position, by turning the shaft u by means of the hand-wheel w , it is firmly held in place by the clamp y , which is rigidly held to the carriage d by means of the hand-screw z . The carriage d and the frame of the table f are formed by T or angle iron, either wrought or cast, and firmly bolted or riveted together for the purpose of constructing same as lightly as possible. The table f is formed by securely fastening to the frame wood, which is covered with felt, so that the glass plates or other materials may not be broken or scratched by clamping same to the table. When the glass or other material is clamped to the table f by means of screw-clamps or other devices for firmly holding the same, the table then is raised by turning the shaft m , upon which are the pinions $l l'$, engaging into the racks $j j'$, as nearly as possible to the required height, to give the desired angle on the edge of the glass or other material to be ground. By then raising or lowering the eccentrics $s s'$ on the shaft u , the angle can be adjusted to the greatest nicety. The carriage d is then moved back and forth on the ways $b b'$, the edge of the glass coming in contact with the revolving stone or mill. The edge is ground away until the desired bevel is obtained, the table f being lowered by means of the racks $j j'$ and the eccentrics $s s'$ as the glass is cut or ground away.

The construction of the adjustable table with the racks and eccentrics also enables the height of the table to be lowered as the stone or mill wears away.

Having now described my invention, what I claim, and desire to secure by Letters Patent, is—

1. In combination, the table f , the eccen-

trics $s s'$, straps $t t'$, hand-wheel w and clamp y , the racks $j j'$, pinions $l l'$, hand-wheel p , and clamp q , and levers $g g'$, and brackets $i i'$, substantially as and for the purpose set forth.

5 2. In combination, the table f , the eccentrics $s s'$, straps $t t'$, the racks $j j'$, and pinions $l l'$, and levers $g g'$, and brackets $i i'$, substantially as and for the purpose herein set forth.

3. In combination, table f , the eccentrics $s s'$, straps $t t'$, hand-wheel w , and clamp y , and

racks $j j'$, with pinions $l l'$, hand-wheel p , and clamp q , substantially as and for the purpose set forth.

In testimony whereof I have hereunto set my hand at New York, county and State of New York.

JAMES H. REED.
